RAILWAY SWITCH CONNECTING ROD

Kenneth J. J. McGowan, Pittsburgh, Pa., assignor to Westinghouse Air Brake Company, Wilmerding, Pa., a corporation of Pennsylvania

Application December 16, 1952, Serial No. 326,333

5 Claims. (Cl. 246—452)

My invention relates to railway track switch operating apparatus and has particular relation to a safety device controlling the operation of switches of the type which are at times trailed.

The present application is a division of my copending application for Letters Patent of the United States, Serial No. 212,995, filed February 27, 1951, for Railway Switch Operating Mechanisms, which has been abandoned.

In certain types of railway yards or on spur tracks, the switches provided for shunting the cars from one track to another are reversed by switch stands which comprise a hand-throw lever coupled through suitable gearing to an operating crank connected by suitable means to the head rod interconnecting the switch points of the switch. Such switches are sometimes trailed causing damage to the switch points and breakage of the switch stand cranks or of the pins used in interconnecting the switches with the switch stands. Subsequent traffic movements over a trailed switch of this type either in a trailing direction or in a facing point direction are hazardous since the switch points are no longer held in either of their two extreme positions. Repairs to the switch and the switch stand are necessary before traffic movements may again be made over the switch.

Various mechanisms have been proposed to permit the trailing of a switch without damage to the switch or its associated switch stand. One such mechanism provides a spring biased plunger and cylinder arrangement interconnecting the head rod of a switch with the operating crank of a switch stand, the plunger being held in position relative to the cylinder by shear pins. A trailing move in this instance breaks off the shear pins permitting the plunger to move the switch to its opposite extreme position. To operate the switch for subsequent moves, the plunger is returned to its operating position against the bias of the charging spring and the broken shear pins replaced.

It is an object of my invention to provide novel and improved switch operating apparatus for automatically reversing a switch when the switch points thereof are moved a predetermined distance by the wheels of a trailing vehicle.

Another object of my invention is to provide novel and improved switch operating apparatus which permits successive improper trailing moves, the switch points being reversed during each successive trailing move.

According to my invention, I interpose between the movable points of the railway switch and the switch stand for moving the switch points to their normal and reverse positions, a mechanism comprising a first member operatively connected to the switch stand and movable thereby and a second member cooperating with said first member and operatively connected to the switch points. The first member includes two symmetrically contoured spring cams and compression members, while the second member includes cam rollers cooperating with the working surfaces of the spring cams. In normal operation, the cam rollers will be held in centrally located recesses

2

or troughs in the spring cams, the bias provided by the compression members holding the rollers within the spring cam troughs so that both the spring cams and the cam rollers will be moved together upon operation of the switch stand to move the switch points to their normal or reverse positions. Should the switch be trailed in either of its two extreme positions, the cam rollers will be moved relative to the spring cams. The contours of the spring cams are such that after a small initial movement of the switch points by the wheels of the trailing vehicle, the increased bias of the compression members will force the rollers over the working surface of the spring cams which will cause the cam rollers to be moved in the same direction to move the switch points over to their extreme opposite position. The bias of the compression members and the spring cams, and the particular contours of the cams, will hold the switch points in their extreme opposite positions until the switch stand is operated to its opposite position. The cam rollers will then be forced back into the center recesses or troughs of the spring cams where they will be held while the switch stand is operated to move the switch points back into their original extreme positions.

Other objects and characteristic features of my invention will become apparent as the description proceeds.

I shall describe one form of a railway switch operating apparatus embodying my invention, and shall then point out the novel features thereof in claims.

In the accompanying drawings:

Fig. 1 is a top plan view showing a switch provided with one form of a railway switch operating mechanism embodying my invention, while

Fig. 2 is a top view showing on an enlarged scale the switch operating mechanism embodying my invention illustrated in Fig. 1 with the cover removed.

Referring to Fig. 1, the reference character A designates a railway track switch comprising two fixed rails 1 and 1a and two movable rails or switch points 2 and 2a, the switch points being connected adjacent their ends by a head rod 3. When the switch occupies its normal position, as illustrated in Fig. 1, the switch point 2 engages the fixed rail 1 and the switch point 2a is spaced from the fixed rail 1a. When the switch A occupies its reverse position, the switch point 2a engages the fixed rail 1a and the switch point 2 is spaced from the fixed rail 1.

Spiked or otherwise securely fastened to the ties adjacent the switch A is a switch stand 4 of the usual type comprising a weighted hand-throw lever 5 secured to the outer end of a shaft 6, the inner end of the shaft having secured thereto a pinion 7 meshing with a gear segment 8. The gear segment 8 is secured to a vertically disposed shaft 9 suitably journaled within the housing 10 provided for the switch stand, the lower end of the shaft 9 extending below the bottom of the housing and having secured thereto a crank arm 11. The crank arm 11 is pivoted to a crank rod 12, the crank rod being secured to the switch operating mechanism embodying my invention and designated generally by the reference character B.

The switch operating mechanism B embodying my invention comprises a housing 13 (Fig. 2) adapted to be closed by a cover 14, the housing being supported for sliding movement on a plate or rollers (not shown) in a well-known manner. The housing 13 is formed with an exterior boss 15 which is suitably drilled and threaded as at 16, for receiving the crank rod 12 fixed to the crank 11 of the switch stand 4, the crank rod being secured by a lock nut 17 and lock washer 18. A connecting rod 19 connected by a link 20 to the head rod 3 of the switch A is slidably received within the housing 13 through a bearing provided in the side of the housing opposite the threaded opening 16. The end

of the connecting rod 19 within the housing 13 is threadedly secured to a bifurcated trolley 22 having rotatably secured thereto as by pins 23, two oppositely extending cam rollers 24. The two cam rollers cooperate with two similar opposing spring cams 25, both cams being made of heavy gauge spring steel, the ends of the cams being mounted with some clearance in recesses 26 provided in the interior walls of the housing 13.

The spring cams 25 are formed with center troughs 25a and moving toward the right in Fig. 2, the troughs 25a are followed by rises or inclines 27a terminating in crests 28a, the crests being followed by declines 29a terminating in end troughs 30a. The left sides of the spring cams 25 are similar, the center troughs 25a being followed by rises 27b, crests 28b, and declines 29b terminating in end troughs 30b. The distance between the center troughs 25a of the spring cams and the end troughs 30a and 30b is equal to the throw of the switch points 2 and 2a. The crests 28a and 28b of the spring cams are approximately one third the distance between the center troughs 25a and the end troughs 30a and 30b.

Cooperating with each of the spring cams 25 are contoured spring retainers or compression members 31 formed to fit the back surfaces of the cams opposite the center troughs 25a. The compression members 31 are urged inwardly toward the center of the housing by coil springs 32 interposed between the members 31 and the end walls of the housing 13, the end walls being formed with bosses 33 for retaining and centering the ends of the springs.

In the operation of the switch operating mechanism B, the bias of the coil springs 32 will retain the cam rollers 24 within the center troughs 25a of the spring cams when the hand-throw lever 5 is operated to move the switch points 2 and 2a to their normal or reverse positions. In the event the switch A is trailed while in its normal position, the movement of switch points 2 and 2a a distance of approximately two inches by the trailing wheels toward their reverse positions will move the connecting rod 19 to the right a sufficient distance to move the cam rollers 24 opposite the crests 28a of the spring cams. The movement of the cam rollers to the right will tend to compress the coil springs 32 and deform the spring cams 25. Upon passing the crests 28a of the spring cams, the horizontal components of the forces exerted by the compressed springs 32 and the deformed spring cams force the rollers farther to the right into the end troughs 30a, the movement of the cam rollers to the right causing the switch points 2 and 2a to be moved to their full reverse position wherein they will be held until the hand-throw lever 5 is operated to its reverse position and returned to its normal position to return the switch points to their normal position. With the switch points 2 and 2a moved to their full reverse positions by the switch operating mechanism B, the operation of the hand-throw lever 5 to its reverse position will move the housing 13 to the right, thereby forcing the cam rollers 24 back past the crests 28a of the spring cams 25 into the center troughs 25a. Operation of the hand-throw lever back to its normal position will move the switch points 2 and 2a to their normal positions in the manner described.

Should the switch A be trailed in its reverse position, the trailed switch points will force the cam rollers 24 to the left past the crests 28b of the spring cams, the deformed spring cams and compressed coil springs 32 forcing the rollers into the end troughs 30b to move the switch points to their full normal position. Operation of the hand-throw lever first to its normal position and then to its reverse position will return the switch points 2 and 2a to their reverse positions.

It will be apparent from the foregoing description of my invention, that successive trailing moves over the switch A may be made, the switch points being reversed during each trailing move. Considering for the moment that the switch A is trailed while in its normal position,

the cam rollers 24 will have been moved into the end trough 30a of the spring cams 25. The switch points 2 and 2a will be in their full reverse positions but the hand-throw lever 5 will be in its position corresponding to the normal position of the switch points. A vehicle trailing the switch A under such circumstances will move the switch points to the left to move the connecting rod 19. The cam rollers 24 will be moved to the left to restore the cam rollers 24 to the center troughs 25a. The positions of the switch points, cam rollers and hand-throw lever now correspond to the normal positions occupied before the switch A was trailed. The mechanism is thus in condition for operation in the normal manner or to provide the automatic reversal described in the event the switch is again trailed. The operation of the switch operating mechanism B will operate in a similar manner when the switch A is trailed while in its reverse position and then subsequently trailed, thereby restoring the mechanism to its reverse position.

In addition to the advantage of permitting successive trailings of the switch, the mechanism hereinabove described may be incorporated between any switch operating mechanism and the associated switch points and will convert the switch to operate for safe trailing movements.

Although I have herein shown and described only one form of railway track switch operating apparatus embodying my invention, it is understood that various changes and modifications may be made therein within the scope 30 of the appended claims without departing from the spirit and scope of my invention.

Having thus described my invention, what I claim is:

1. Apparatus for interconnecting an element of a railway switch with an element of a switch stand, comprising a deformable spring cam for connection with one of said elements and having symmetrical working surfaces about a median point, a cam follower for connection with the other of said elements and cooperating with the working surfaces of said cam, and resilient means 35 biasing the median point of said cam in engagement with said cam follower to maintain said cam follower in engagement with said cam at its median point when said switch stand element is operated to throw said switch, the working surfaces of said cam being such that when said switch element is moved by a trailing vehicle the bias of said resilient means is increased and said cam is deformed due to the relative movement between said cam follower and said working surfaces, a predetermined relative movement between said working surfaces and said cam follower permitting the stressed resilient means 40 and the deformed cam to increase the relative movement between said working surfaces and said cam follower to reverse said switch.

2. In combination with a railway switch and a switch

55 operating mechanism operable between two extreme positions for moving said switch to its normal and reverse positions, two symmetrical, opposing spring cams operatively connected with said operating mechanism, a cam follower cooperating with said spring cams and operatively connected with said switch; and resilient means 60 cooperating with each of said spring cams tending to bias said cams toward each other, said resilient means and spring cams being such that said cam follower is retained relative to said cams when said cams are moved by said operating mechanism to move said switch to its normal and reverse positions; the trailing of said switch moving said cam follower in a corresponding direction to move said cam follower relative to said cams against the bias of said resilient means and deforming said cams, the movement of said cam follower a predetermined distance 65 by said trailed switch permitting the biased resilient means and deformed spring cams to move said cam follower an additional distance in the direction the cam follower was moved by the trailed switch to reverse said

70 switch.

3. In combination with a railway switch and a switch operating mechanism operable between two extreme positions for moving said switch to its normal and reverse positions, two symmetrical, opposing spring cams operatively connected with said operating mechanism, each of said cams having center troughs and end troughs with crests therebetween, the distances between the center trough and end troughs of each spring cam being approximately equal to the throw of said switch, the crests between the center and end troughs of each spring cam being approximately one third the distance from the center trough to the end troughs; a cam follower engaging both of said spring cams and operatively connected with said switch; and resilient means cooperating with each of said spring cams adjacent the center troughs thereof tending to bias said cams toward each other, said resilient means and spring cams being such that said rollers of the cam follower are retained in the center troughs of said cams when said housing member is moved by said operating mechanism to move said switch to its normal and reverse positions; the trailing of said switch moving said cam follower in a corresponding direction to move said cam rollers out of said center troughs of said cams against the bias of said resilient means and deforming said cams, the movement of said rollers past the crests of said spring cams permitting the biased resilient means and deformed spring cams to move said cam follower into engagement with the end troughs of said cams thereby reversing said switch; the operation of said operating mechanism to its extreme position corresponding to the extreme position to which the trailed switch was moved, moving said cams relative to said cam follower to force said cam follower back into engagement with the center troughs of said spring cams.

4. In combination with a railway switch and a switch operating mechanism operable between two extreme positions for moving said switch to its normal and reverse positions, a housing member operatively connected with said operating mechanism; two symmetrical, opposing spring cams within said housing member; each of said cams having center troughs and end troughs with crests therebetween, the distances between the center trough and end troughs of each spring cam being approximately equal to the throw of said switch, the crests between the center and end troughs of each spring cam being a predetermined fractional portion of the distance between the center trough and the end troughs; a cam follower including

opposing cam rollers cooperating with said spring cams and operatively connected with said switch; and resilient means cooperating with each of said spring cams adjacent the center troughs thereof tending to bias said cams toward each other, said resilient means and spring cams being such that said rollers of the cam follower are retained in the center troughs of said cams when said housing member is moved by said operating mechanism to move said switch to its normal and reverse positions; the trailing of said switch moving said cam follower in a corresponding direction to move said cam rollers out of said center troughs of said cams against the bias of said resilient means and deforming said cams, the movement of said rollers past the crests of said spring cams permitting the biased resilient means and deformed spring cams to move said rollers into the end troughs of said cams thereby reversing said switch; the operation of said operating mechanism to its extreme position corresponding to the extreme position to which the trailed switch was moved, moving said housing member relative to said cam follower to force said cam rollers back into the center troughs of said spring cams.

5. Apparatus for interconnecting an element of a railway switch with an element of a switch stand, comprising two deformable spring cams for connection with one of said elements disposed in confronting relationship, each of said cams having a center trough and two end troughs with crests therebetween, the distance between said center trough and the two end troughs being approximately equal to the throw of the railway switch, the crests between said troughs being a predetermined fractional portion of the distance between said center trough and said end troughs, a cam follower cooperating with the surfaces of both said cams for connection with the other of said elements, and resilient means cooperating with each of said cams to bias said cams toward each other and into engagement with said cam follower.
